DRAFTING INSTRUMENT

Edward F. Campbell, Jeffersonville, Ind.

Application December 9, 1949, Serial No. 132,185

4 Claims. (Cl. 33—104)

(Granted under the act of March 3, 1883, as
amended April 30, 1928; 370 O. G. 757)

1

The invention described herein, if patented, may be manufactured and used by or for the Government for governmental purposes without the payment to me of any royalty thereon.

This invention relates to drafting instruments and among other objects, aims to provide a device which facilitates the making of dotted pencil lines of different characteristics and which is designed to obviate scraping graphite from pencil points, which would smear or soil drawings. Other objects will be obvious from the following description of the preferred embodiment of the invention shown in the accompanying drawings forming a part of this specification.

In said drawings:

Fig. 1 is a plan view of the instrument;

Fig. 2 is a fragmentary plan view on a larger scale of one of the removable line-dotting attachments:

Fig. 3 is an enlarged section on line 3-3 of Fig. 1.

Fig. 4 is an enlarged section on line 4-4 of Fig. 2; and

Fig. 5 is an enlarged section on line 5-5 of Fig. 1.

Referring particularly to the drawings, the preferred embodiment of the invention comprises a transparent flat plastic body 6 which may be a 30°-60° right triangle as shown or may have many other shapes such as that of a 45° right triangle, an isosceles triangle, a protractor, a square or oblong, or even a circle. Its edges may be marked with scales in inches or centimeters and fractions thereof (not shown). This triangle is provided with three slots each parallel to one of its sides but having no communication with the others. The purpose of these slots will be explained presently.

On the underside 7, that is, the surface adjacent the drawing paper, the body 6 is provided with pairs of grooves 8, 9, 10, 11, 12, 13, each pair extending parallel to one of the sides of the triangle but spaced therefrom, and terminating short of the other two sides. These grooves have depths of about two-thirds or three-fourths of the thickness of the body and make angles of about 60° or 120° with the plane of the underside 7, as shown in Fig. 3, so that the grooves of each pair converge upwardly.

Interlocked with each converging pair of grooves is a resilient channel-shaped insert or strip 14, 15, 16, each strip being preferably of plastic and having converging longitudinal edge flanges 17, 18 adapted to enter the grooves when the strip has been bent or flexed transversely and

adapted when released to lock with the groove walls by reason of its resilience. Each plastic strip has a thickness of less than 1 mm. and any convenient length as indicated by the dimensions of the slots in body 6. The purpose of strips 14, 15, 16 is to facilitate forming dotted or dot-and-dash lines and to this end each strip has one or more series of perforations 19, 20 (or 22 or 24) of different sizes and spacing. Perforations 19, 20 are primarily for making two different types of dotted lines by running a pencil (in the manner indicated in Fig. 4) rapidly over either series of perforations while guided by the appropriate edge of slot 25. Perforations 22 in strip 15 are circular and are primarily for making fine dotted lines with the pencil moved along slot 26, while perforations 24 in strip 16 facilitate making dot-and-dash lines in conjunction with slot 27. Slots 26 and 27 are narrower than slot 25 and only one series of perforations are associated with these narrow slots. It will be clear that many other arrangements and dimensions of the perforations and slots may be employed. Obviously each strip 14, 15, 16 is easily removed manually for replacement with a different strip. If desired, after the strips are taken off, the longitudinal edges of slots 25, 26, 27 may be used for drawing straight lines, and as the several slots may be of many different widths they may be employed for making parallel lines spaced different known distances apart without the necessity of measuring such distances.

35 While the illustrative strips are snapped on and off the body 6, if preferred each pair of grooves 8, 9, or 10, 11, or 12, 13 may extend to one edge only of the triangle and the corresponding strip may be engaged therewith by pushing or sliding it endwise into the groove ends where exposed at a triangle edge. This will be understood without illustration.

40 As shown in Fig. 4, the edges of the strips which define or bound the perforations 19-24 are curved downwardly to cause the lead pencil point to ride over the edges without scraping or abrading any substantial amount of graphite from the point, the result being that no graphite dust is deposited on the drawing paper by ordinary use of the instrument. It is of course clear that the paper would be smeared or soiled if such dust were formed.

50 In the central portion of the triangle or other body 6, several circular series of perforations 30, 31, 32, 33 are shown all of which surround a hole 34 which is at the center of the several circles and is adapted to receive the point of a compass. After placing the compass point in hole 34

the draftsman may make dotted circles of a considerable range of diameters by merely running the lead around over the perforations. The thickness of the body 6 is considerably reduced in the area containing perforations 30, 31, 32, 33, as indicated at 35, Figs. 1 and 5, so that the compass lead may enter every perforation as it passes around the circle. Arcuate or curved dotted lines may be made possible by the provision of other perforations extending in curved lines (not shown). These supplementary perforations may be dispensed with and a single large hole for the draftsman's fingers may be provided, as is conventional in triangles. Other changes may be made within the scope of the appended claims.

What I claim is:

1. A drafting instrument facilitating the making of broken lines comprising a body having a flat under surface provided with a pair of parallel grooves extending up into the body, the body also having a straight slot extending between said grooves, an elongated flexible strip having flanges along two longitudinal edges which extend upwardly into the grooves, the shapes of the grooves and flanges being complementary and such that the strip is removably locked on the body, the strip having a very thin area between its flanges and having spaced perforations in said thin area, so that a pencil point may be thrust through the slot from above and may be run along the slot and over the perforations through which the pencil point passes to mark a paper sheet placed under the body with dots or dashes spaced in accordance with the spacing of the perforations.

2. The invention as defined in claim 1, wherein in the body has the shape of a triangle and there are three pairs of grooves, three slots each associated with one pair of grooves, and three strips, each slot and associated pair of grooves being parallel to one of the sides of the triangle, the slots having no communication with each other, and the grooves of each pair converging upwardly.

3. A ruling device for draftsmen comprising a flat body portion provided with an elongated slot in one face thereof and a relatively narrow elongated groove located on each side of said slot and parallel therewith, an elongated strip of material provided with a series of openings or perforations extending longitudinally of said strip, flanges on the longitudinal edges of said strip disposed in said relatively narrow grooves, the shapes of the relatively narrow grooves and the flanges being complementary and such that the strip is detachably connected to the flat body portion.

4. A ruling device for draftsmen comprising a flat body portion provided with a slot and a pair of parallel grooves in one face thereof and on either side of said slot, an elongated strip of thin resilient material provided with an elongated series of openings or perforations, and a pair of flanges integral with the strip and extending longitudinally thereof and interlocking with said grooves when the strip is flexed transversely to releasably secure said strip to said body portion, the resilience of the strip and the interlocking flanges and grooves constituting the sole means for securing the strip, and the strip being removable manually whenever it is flexed transversely and its flanges are moved out of interlocking engagement with said grooves.

EDWARD F. CAMPBELL.
